UNITED STATES PATENT OFFICE.

RAGNAR O. W. LUNDIN, OF NORTH ATTLEBORO, MASSACHUSETTS, ASSIGNOR TO BARBER ELECTRIC MANUFACTURING COMPANY, OF NORTH ATTLEBORO, MASSACHUSETTS.

ELECTRIC SWITCH.

Application filed August 25, 1927. Serial No. 215,440

The present invention relates to electric switches, and consists more particularly of an improved construction of means for actuating the blade or blades of an electric switch.

It is common in practice to enclose the electric switch of a house lighting or service system within a closed box. The switch within the box is operated by external means, and the present invention is especially applicable to switches of the so enclosed type.

The chief objects of the invention, amongst others, are to provide a simple and efficient means for actuating the switch blade or blades and for coupling the same with said actuating means, and to provide a coupling means, which may be readily assembled, connected and maintained in its connected position.

An embodiment of the invention will be hereinafter more fully described and set forth, and which embodiment is illustrated by the accompanying drawings, wherein:

Figure 1 is a sectional view showing the switch and connector, the switch being mounted on a porcelain base contained within a box of which only a portion is shown,

Fig. 2 is a front elevation of the same construction shown in Figure 1, and

Figures 3 and 4 are detail views showing the construction of the coupling device.

Referring to the said drawings, 1 is the usual porcelain base mounted within the box 2 of which only a portion of the bottom is shown in the drawings. 3 represents the fixed contacts which are secured to the base 1, and 4 is a switch blade pivotally connected at 5 to one of the fixed contacts 3. 6 is the bail or rod having an external handle, which is usually employed for operating the switch externally. This bail passes through the box and is pivoted, and so formed and located that the required throw is obtained to operate the switch.

The coupling device consists of an intermediate piece 7, which is riveted at 8 to the switch blade 4, and said piece is composed of insulating material. The connecting device 9 is formed of sheet metal strip blanked out in the shape as shown in Figure 4, and which

blank has wings 10 both being perforated at 11 and connected together by an integral portion 12. This blank is doubled over to form a U-shaped piece and preferably in assembling the switch blade within the box, 55 said piece 9 is threaded on the bail 6 through the slots 11. The insulating piece 7 is riveted to the knife blade, and in assembling the switch, the base carrying the switch is first secured within the box, and then, when 60 the switch is in a certain position, the connector 9 is united with the insulating piece 7 by means of the connecting portion 12 being engaged within the slot 13 of said insulating piece 7. 65

The connection of the actuator, it will be seen, is readily effected and there is no chance of this connector becoming accidentally disengaged. It will be understood that it is usually desirable that there should be slight lost motion in the connection of the switch actuator with the coupling means, and for this purpose the loose connection afforded by the elongated slot 11 is utilized. This loose connection is particularly of advantage when a plurality of knife blades are connected for simultaneous operation because by means of this connection, certain inequalities are compensated whereby better contact is obtained between the switch blade 70 and the fixed contacts. The said connecting or end member 9 may be loosely connected to the insulating piece 7 so as to be readily detachable, but if required said member may be pressed so as to tightly engage the piece 7 so that said actuator cannot be easily detached. 75

Various modifications may be made in the construction and arrangement of the hereinbefore described device without departing 90 from the spirit of the invention, and it will be understood that any modification coming fairly within the terms of the appended claims shall be covered thereby.

I claim—

1. In an electric switch, a switch blade, an actuating rod for said blade, coupling means between said blade and said actuating rod; said means comprising a slotted end piece mounted on said rod and an inter- 100

mediate insulating piece rigidly secured to said blade and detachably secured to said end piece.

2. In an electric switch, a switch blade, an actuator for said switch blade, coupling means operatively connected to said actuator, said means comprising an intermediate insulating piece secured to said blade and an end connecting device composed of sheet

metal bent to form a U-shaped member; 10 said member engaging a slot in said intermediate member, and said end member having a slot in which said actuator is engaged.

Signed at North Attleboro, county of Bristol, State of Massachusetts, this 27th 15 day of July, 1927.

RAGNAR O. W. LUNDIN.
